[57] CLAIM

The ornamental design for a secure telephone modem
or similar article, as shown and described.

DESCRIPTION

FIG. 1 is a top, left front perspective view of a secure
telephone modem or similar article showing our new
design;

FIG. 2 is a right elevational view thereof, on an
enlarged scale, the left side being a mirror image;

FIG. 3 is a rear elevational view thereof, on an enlarged
scale;

FIG. 4 is a bottom plan view thereof, on an enlarged
scale.

FIG. 1

FIG. 2

FIG. 3
